UNITED STATES PATENT OFFICE

145,451

DESIGN FOR A DECK HOUSE FOR A SHIP

Clyde M. Leavitt, Pascagoula, Miss., assignor to
Ingalls Shipbuilding Corporation, a corporation
of Delaware.

Application December 22, 1945, Serial No. 124,951

Term of patent 14 years

(Cl. D71—1)

To all whom it may concern:

Be it known that I, Clyde M. Leavitt, a citizen of the United States and resident of Pascagoula, in the county of Jackson and State of Mississippi, have invented a new, original, and ornamental Design for a Deck House for a Ship, of which the following is a specification, reference being had to the accompanying drawings, forming a part thereof.

This application is a continuation in part of my previously filed application, Serial No. D117,315, filed January 6, 1945.

In the drawings,

Fig. 1 is a perspective view of a deck house for a ship showing my new design and looking from the port side forward; and

Fig. 2 is a view of the forward end of the deck house for a ship.

The port and starboard sides of the deck house are the same in construction and appearance.

I claim:

The ornamental design for a deck house for a ship, substantially as shown and described.

CLYDE M. LEAVITT.
